UNITED STATES PATENT OFFICE.

JOSIAH DOW, OF PHILADELPHIA, PENNSYLVANIA.

GENERATING AND UTILIZING MOTIVE FLUID UNDER PRESSURE.

1,232,247.

Specification of Letters Patent.

Patented July 3, 1917.

Application filed September 18, 1916. Serial No. 120,726.

To all whom it may concern:

Be it known that I, JOSIAH Dow, a citizen of the United States, residing in Philadelphia, Pennsylvania, have invented certain improvements in Generating and Utilizing Motive Fluid under Pressure, of which the following is a specification.

My invention consists of certain improvements in the method of and apparatus for generating pressure which constitutes the subject of my application for patent, Serial No. 86,955, filed March 27th, 1916.

In carrying out the invention forming the subject of my previous application a mixture of alcohol vapor and air, both under pressure, was burned and the products of combustion, greatly expanded by comparison with the original body of alcohol vapor and air, constituted the motive fluid under pressure which was produced for subsequent use in a suitable engine. Incidental to such production water vapor was added to the products of combustion for the purpose of absorbing excess of heat produced in the confined spaces of the generator.

The object of my invention is to render the process of power generation and utilization automatic by freeing it from dependence upon any external source of supply for the water or water vapor to be added to the products of combustion, and this object I attain by reason of the chemical composition of the motive fluid exhausted from the engine in which it was used for the development of power.

In the accompanying drawing—

Figure 1 is a diagrammatic representation of apparatus for the production and utilization of motive fluid under pressure in accordance with my present invention, and

Fig. 2 is a longitudinal sectional view on a larger scale, of one of the elements of said apparatus.

There are certain hydrocarbons whose combustion can be effected without production of free carbon, and as alcohol is the most available of such hydrocarbons it has been adopted by me as typical and will hereafter be the one referred to, although my invention is not necessarily limited thereto.

In the accompanying drawing, 1 represents a pressure generator, 2 an alcohol supply pipe, 3 an air supply pipe, 4 a water supply pipe, 5 a pipe for conveying the motive fluid under pressure to the point of utilization, 6 a pipe for furnishing an initial sup-

ply of air under pressure, 7 a vessel in which such air under pressure is caused to impart like pressure to the alcohol supply, and 8 a water reservoir connected by branch 9 to the air pressure supply pipe 3 so that corresponding pressure will be imparted to the water in said reservoir. All of these parts are similar in construction and operation to those found in my preceding application; hence a more detailed description of them here will be unnecessary.

The engine in which the pressure of the motive fluid is utilized for the production of power is represented at 10, the exhaust pipe 11 from this engine communicating with a condenser 12 and the latter being also in communication through a pipe 13 with a pump 14 whose discharge pipe 15 communicates with the water reservoir 8.

The chemical formula for ethyl alcohol is C_2H_5OH and when the mixture of alcohol and air is burned in the generator 1 the products of combustion are carbon dioxide and water, the latter being, of course, in the form of vapor because of the high degree of heat of said products of combustion.

The motive fluid exhausted from the engine 10 is therefore carbonic acid and water vapor and in order to recover the water in liquid form it is only necessary to free the carbonic acid from the water vapor and reduce the temperature of the latter below the boiling point.

In order to effect the rapid attainment of this result I maintain the exhaust at atmospheric pressure so that the rapid evaporation of the carbonic acid will quickly reduce the temperature of the water vapor, and I further subject the exhaust to the action of an independent cooling agent, such as air or water.

With this object in view the condenser 12 is constructed as shown in Fig. 2, on reference to which it will be observed that said condenser comprises a casing 16 containing upper, lower and intermediate chambers 20, 21 and 22, respectively, these chambers being separated from one another by heads 17 and 18 and the chambers 20 and 21 being connected to one another by means of tubes 19 extending from one head to the other across the chamber 22, the chamber 20 being in communication with the exhaust pipe 11 of the engine.

Surrounding the lower portion of the casing 16 is a well 26 open to the air at the top

and in free communication with the chamber 21, the lower portion of this well discharging through the pipe 13.

Air, water or other cooling agent is admitted to the chamber 22 through a pipe 24 and is discharged therefrom through a pipe 25, whereby this cooling agent circulates in contact with the tubes 19. As the well 26 is open to the atmosphere the motive fluid exhausted from the engine 10 is free from pressure as soon as it leaves said engine and rapid evaporation of the carbonic acid at once begins, with corresponding rapid cooling of the water vapor, so that by the time the exhaust reaches the chamber 21 of the condenser the temperature of the water vapor will be reduced to the point of liquefaction, the circulation of the cooling agent in contact with the tubes 19 contributing to the attainment of this result.

Instead of the specific form of condenser described I can use any form of conduit in which the desired evaporation of the carbonic acid can be effected under the same conditions.

The water from the well 26 passes through the pipe 13 to the pump 14 and is thereby fed under pressure to the reservoir 8, the volume of water thus returned being sufficient to maintain the supply of water or water vapor needed for admixture with the products of combustion in the generator, in order to absorb the excess of heat, no extraneous supply of water being necessary.

I claim:

1. The mode herein described of producing and utilizing motive fluid under pressure, said mode consisting in effecting combustion of alcohol, using the products of combustion as motive fluid in an engine, and adding to the products of combustion water derived from motive fluid exhausted from said engine.

2. The mode herein described of producing and utilizing motive fluid under pressure, said mode consisting in effecting combustion of alcohol, utilizing the products of

combustion as motive fluid in an engine, separating from one another the carbonic acid and water vapor constituting the motive fluid exhausted from said engine, and returning the resultant water to the products of combustion for the purpose of absorbing excess of heat.

3. The mode herein described of producing and utilizing motive fluid under pressure, said mode consisting in effecting combustion of alcohol, utilizing the products of combustion as motive fluid in an engine, evaporating, at atmospheric pressure, the carbonic acid from the water vapor in the motive fluid exhausted from said engine, and returning the resultant water to the products of combustion for the purpose of absorbing excess of heat.

4. The mode herein described of producing and utilizing motive fluid under pressure, said mode consisting in effecting combustion of alcohol, utilizing the products of combustion as motive fluid in an engine, liquefying the water vapor contained in the motive fluid exhausted from said engine by freeing the carbonic acid therefrom at atmospheric pressure, and at the same time reducing the temperature of the exhaust by a cooling agent derived from an outside source, and returning the resultant water to the products of combustion for the purpose of absorbing excess of heat.

5. The combination, in apparatus for the production and utilization of motive fluid under pressure, of a generator having an alcohol burner, an engine for utilizing the motive fluid under pressure thereby produced, a condenser for freeing the carbonic acid from the motive fluid exhausted from said engine, and means for returning the resultant water, under pressure, to the products of combustion in the generator for absorbing excess of heat therein.

In testimony whereof, I have signed my name to this specification.

JOSIAH DOW.
